FINGER RING

Robert N. Gibeault, 40 Hunting St.,
North Attleboro, Mass.

Filed June 22, 1960, Ser. No. 61,075

Term of patent 14 years

(Cl. D45—10)

Fig. 1

Fig. 2

Fig. 3

Fig. 4

Fig. 1 is a front elevation of a finger ring embodying my new design;

Fig. 2 is a view in side elevation thereof;

Fig. 3 is a perspective view thereof; and

Fig. 4 is a top plan view thereof.

I claim:

The ornamental design for a finger ring, substantially as shown.
